Primary Examiner — Jennifer Rivard(74) *Attorney, Agent, or Firm* — Jay A. Krebs(57) **CLAIM**

The ornamental design for a combination shaving and trimming device, as shown and described.

DESCRIPTION

FIG. 1 is a perspective view as seen from the top, front, and left side of an arrangement of a trimmer and a razor attachment in packaging for a combination shaving and trimming device showing our design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a perspective view of a second embodiment;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The broken lines shown in the drawings illustrate the environment of the article and form no part of the claimed design.
